UNITED STATES PATENT OFFICE.

CHARLES A. DOUD, OF UNDERWOOD, WYOMING.

EXCAVATING-MACHINE.

1,391,532.

Specification of Letters Patent. Patented Sept. 20, 1921.

Application filed October 3, 1919. Serial No. 328,108.

To all whom it may concern:

Be it known that I, CHARLES A. DOUD, a citizen of the United States, residing at Underwood, in the county of Laramie and State of Wyoming, have invented certain new and useful Improvements in an Excavating-Machine, of which the following is a specification.

This invention relates to improvements in excavating machines, and has for one of its objects to improve the construction and increase the efficiency and utility of devices of this character.

Another object of the invention is to provide a device of this character capable of cutting or operating simultaneously at two independent locations and elevating the earth thus displaced and depositing it in a single receptacle or receiver.

Another object of the invention is to provide a device of this character including a receptacle for the displaced and elevated earth swingingly mounted to enable it to be tilted to discharge the contents.

Another object of the invention is to provide a device of this character associated with a tractor, preferably of the caterpillar form, so that the machine after receiving its load can be moved to any distance for discharging the same.

With these and other objects in view, the invention consists in certain novel features of construction as hereinafter shown and described and then specifically pointed out in the claims, and in the drawings illustrating the preferred embodiment of the invention.

Figure 1 is a side elevation.

Fig. 2 is a rear elevation of the upper portion of one of the elevator devices.

Fig. 3 is a section on the line 3-3 of Fig. 2.

Fig. 4 is an enlarged elevation of a portion of the plow elevating mechanism.

Fig. 5 is a section on the line 5-5 of Fig. 4.

Fig. 6 is a rear elevation.

Fig. 7 is a sectional detail of the lower portion of one of the elevators.

Fig. 8 is a perspective view of a portion of the receiver for the elevated earth and one of its locking devices, illustrating the construction and operation.

Fig. 9 is a plan view.

Figs. 10 and 11 are enlarged detail views, 55 illustrating the construction and operation of the locking and tripping mechanism for the tilting earth receptacle.

Fig. 12 is an end view of the parts arranged as in Fig. 10 with the dumping receptacle in section.

The improved apparatus is preferably mounted upon the frame of a tractor of the caterpillar form, the supporting frame of the tractor including spaced side members 65 10-11 arranged to support the traveling tracks or "treads," indicated conventionally at 12.

The frame members 10-11 are arranged in pairs at each side of the chains of treads, 70 and coupled by transverse struts or beams 13-14.

Rising from the outer frame members 10-11 are upright supporting members 15-16 converging toward their upper ends 75 and provided with stub shafts 17.

Two sets or pairs of the supports 15-16 are employed, one set at each side of the chain devices, as represented in Figs. 6 and 9.

Attached to each of the members 15 is a bracket like member 18 directed outwardly and upwardly. The members 15 and the inner members 16 are provided with bearings 19 to support the inner ends of shafts 17. 85 While the upper ends of the outer members 16 and the bracket members 18 are likewise provided with bearings 20 to support the outer ends of the same shafts.

Rising from the frame members 10-11 90 at their forward ends are other uprights 21, the latter connected by their upper ends by brace members 22 to the uprights 16 and brackets 18.

Obliquely directed braces 23 are also arranged between a centering bracket 24 and the uprights 15 and 21, the bracket being rigidly attached to the adjacent portion of the members 11.

The members 15-16 and 21 together with 100 the brackets 18 and braces 22 and 23 form a skeleton frame for supporting the excavating and elevating mechanism and the receptacle for the excavated and elevated material.

The excavator portions of the improved 105 apparatus are arranged to operate exter-

nally of the chain or tread drive devices 12 and in advance of the forward lines thereof.

Each excavator device comprises a scraper like member 25 with vertical sides and pointed at the forward end, and preferably formed with a "rooting" or digging "nose" 26. The upper portions of the member 25 are inclined upwardly toward the rear and coupled by spaced radius bars 27-28 to the frame in any suitable manner, for instance by bracket devices 29.

Mounted upon the forward ends of the inner frame members 10 are standard frames 30 each carrying a stub shaft 31 which supports an internal gear wheel 32. The gear is formed with oppositely disposed vacant or toothless spaces 33 as shown in Fig. 4. Suitably supported for rotation upon the standards 30 is a transverse shaft 34 carrying pinions 35 engagable with the gears of the wheel 32.

The shaft 34 extends entirely across the framework and is adapted to be constantly rotated from the motor of the tractor, for instance by a longitudinal shaft 36 and bevel gears 37.

When the member 32 is set with its vacant spaces 33 as shown in Figs. 4 and 5, the pinions 35 will run as idlers, as will be obvious.

Mounted upon the wheel 32 intermediate the vacant spaces 33 are spring controlled lock bolts 38 extending normally beyond the line of the rim of the wheel 32 and offset at their outer ends to engage alternately in notches or seats in the adjacent face of the frame member 10, as illustrated in Fig. 1. The lock bolt which for the time being is downward engages in the seat in the frame member, while the other bolt is directed upwardly and is inoperative. Projecting from the face of each of the wheels 32 is a crank pin 39, and rotatably coupled to each crank pin is a connecting rod or strap 40 forked, and coupled respectively to the scrapers or "rooters" 25.

When the wheels 32 are arranged with the crank pins in their downward positions the scraper members 25 will be held in their downward or operative positions as shown in Fig. 1. When thus arranged the adjacent lock bolt 38 will be engaged in the seat in the member 10 and "lock" the scraper or rooter in its downward or operative position and the pinions 35 opposite one of the vacant spaces 33 and thus running idle.

When the wheels 32 are arranged with their crank pins in upper position, the scrapers and their attachments will be elevated above the ground or disposed in inoperative position with the other lock bolt 38 in the seat in the frame and the pinions 35 running idle in the other vacant spaces.

Means are provided for releasing the lock bolts 38 and rotating the wheel 32 to suffi-

cient extent to cause the toothed portions of the wheel to be disposed in mesh with the pinions and thus cause the wheel to be rotated to a sufficient extent to reverse the positions of the lock bolts. An approved means for accomplishing this result consists of a pull rod 41 slidably supported upon the frame members 10, one at each side, and each rod formed with an inclined face 42 and an upwardly directed terminal lip 43.

Each rod is provided with a suitable operative lever 44 provided with a pull spring 45 to maintain the rods yieldably in the forward positions.

The rods 41 are so arranged that the inclined faces 42 pass beneath the lock bolt which for the time being is downward and elevates it out of the recess in the frame 10 and the lip 43 engages the bolt and rotates the wheel to a sufficient extent to cause the adjacent toothed portions to be engaged with the constantly revolving pinion 35 and rotate the wheel one half a revolution or until the other lock bolts engage in the recess in the frame and the other vacant spaces are disposed opposite the pinions. In the meantime the rods are returned by the springs 45 to the former positions out of the way of the downwardly moving bolt.

Thus the scrapers may be quickly disposed in operative or inoperative position by merely pulling the levers 44 rearwardly and then releasing them. By arranging one of the pull rods at each side, the scrapers may be independently operated as will be obvious.

The brace members 23 support "strut" members 46 to form supports for main drive shafts 47.

Mounted upon the stub shafts 17 are chain wheels 48 and 49, and mounted upon the drive shaft 47 and between each pair of the frame members 16, is a drum 50. Each of the chain wheels and the drums are formed with a plurality of flat faces, preferably six for each wheel and drum, and the links of the chains which operate around the wheels and drums, represented conventionally at 51, correspond in length to the flat faces of the drums and wheels.

Attached to each alternate opposite pair of the links 51, is a bucket 52, each bucket comprising a closed outer wall or bottom, closed side portions and one closed end, leaving the other end and the remaining wall open.

The buckets are attached to the links 51 with their open sides inwardly, or next to the space between the chains.

Attached to the members 16 is a sheet metal plate 53 against which the open sides of the buckets operate at the upwardly moving portions of the chains, the plate thus serving as a closure to all of the buckets during their upward or loaded movement.

The shaft 47 is rotated by any suitable power, for instance the motor which drives the tractor, and transmits its motion to the chains and buckets in the direction indicated by the arrow in Fig. 1.

The flat faces of the drums 50 correspond in length to the links 51 of the chains, consequently correspond to the open sides of the buckets, so that as the chains of buckets 10 pass around the drums, the flat faces of the drums consecutively form closures for the open inner sides of the buckets to prevent the earth from escaping.

The members 25 are of solid construction, 15 to withstand the severe strains to which they will be subjected and located upon the inclined upper face of each is a guide chute for the excavating material each formed in two portions 54 and 55 hingedly united at 56. 20 The portion 54 of the chute is attached to the scraper or "rooter" part 25 while the portion 55 is movably pivoted at 57 to the frame members 11, the pivot 57 working in a slot as shown in Fig. 1, to provide the 25 necessary change of position when the member 25 is adjusted by the action of the wheels 32 before described. At its discharge end the bottom of the portion 55 of the chute is extended and curved, downwardly as shown 30 at 58 to prevent the elevation buckets from striking the chute as hereafter explained.

Attached to the framework of the tractor in any suitable manner are segmental tracks 59, the centers of the segments being indicated at 60 in the brackets 24. The tracks 35 59 are each formed in two parts in spaced relation.

Mounted to swing upon the centering members 60 are standards or bars 61, each 40 bar extending between the spaced members of the segmental tracks and each carrying a bearing roller 62 traveling upon one portion of the tracks.

Disposed between the chains of buckets is 45 a receptacle, represented as a whole at 63 for the excavated and elevated material, the receptacle being rigidly connected as shown at 64 to the standards 61 and swinging therewith upon the centering member 60 into the 50 position indicated by dotted lines in Fig. 1, when the load is to be discharged as hereafter explained.

The receptacle is closed at the bottom sides and one end and open at the other end. 55 Pivoted at 65 to the upper ends of the members 21 is a closure 66 for the open end of the receptacle 63 when the latter is in level or load receiving position.

Pivoted at 67 to the receptacle 63 and at 60 68 to the swinging closure 66 are links or bars 69.

Extending through the frame members 15 is a rock shaft or rod 70 having an operating handle 71.

Attached to the shaft 70 at one or more

points are hooks 72, engaging, when the receptacle is in horizontal or load receiving position, over stop pins 73 on the receptacle.

The standards 61 are attached to the receptacle 63 slightly nearer the closed end than the open end so that a major quantity of the load will be disposed forwardly of the standards. Thus the receptacle is rendered self-tilting when the catch devices 72 are disconnected from the pins 73, as hereafter explained.

Pivoted at one end at 74 to one or both of the segmental tracks 59 is a locking member formed in two parts 75 and 76 80 hingedly united at 77. The free end of the shorter part 76 is recessed as shown at 78 to receive a stop pin 79 extending from the member 63.

A spring 80 is arranged to exert its force 85 to hold the jointed member 75 and 76 yieldably in outward position with its free end 76 normally in advance of the outer face of the track and into the path of the pin 79. Thus when the receptacle 63 is moved into dumping position, as shown by dotted lines in Fig. 1 and in full lines in Fig. 11, the pin 79 will pass over the members 75-76 and depress the latter against the resistance of the spring 80 and when the pin 79 has been moved beyond the recessed end 78 of the lock device, the reaction of the spring 80 will restore the lock lever to its outward position with the recessed end 78 extending again into the path of the pin 79 and thus preventing the 90 95 return movement of the receptacle.

The complete dumping of the load is thus insured.

Located between the spaced members which form each of the segmental tracks 105 59 is a buffer spring 81 to receive the impact of the members 60 when the receptacle 63 is moved into dumping position and prevent unnecessary jarring or concussions.

Pivoted at 82 to the adjacent member 59 110 is a bell crank lever 83 one arm of latter being connected to member 75-76 preferably at its joint 77 by a link 84 and the other arm supplied with a pull rod or cable 85 leading to a point convenient to the operator. 115

A pull cable 86 is attached relatively to one of the members 61, preferably through the medium of a segmental bracket 87, and leads at one end of a relatively powerful 120 pull spring 88, the latter being attached at the other end a standard 89 supported on to the framework of the machine.

The major portion of the load of the receptacle being disposed toward the open or discharge end, causes the receptacle to be automatically moved into discharging position when the catch devices 72 are released and against the resistance of the spring 88 which is strong enough to pull the empty 125 130

receptacle into receiving position after the load is dumped, but which will not be strong enough to resist the gravity of the loaded receptacle, as hereafter more fully explained.

At their upper ends the plates 53 are bent over into trough shaped portions 90 inclined toward the receptacle 63 and discharging into the same. The outer chain 10 wheels of each series are preferably formed without spokes or in disk form and operate as closures for the outer ends of the troughs to prevent the escape of the excavated material outwardly.

15 With an apparatus thus constructed the operation is as follows:

The members 32 are operated to elevate the diggers 25 above the surface of the ground and the machine moved to the locality where the excavation is to be made.

20 The members 25 are then lowered into operative position and the machine moved forwardly causing the "rooters" or plows 25 to excavate or form furrows at each side.

25 The excavated or loosened earth is forced over the chutes 54—55 and into the buckets 52 as they pass around the drums 50, the faces of the drums and the plate 53 holding the earth within the buckets as they pass 30 upwardly and dumping their loads consecutively into the chutes 90 and thence into the receptacle 63 from each side.

The machine thus cuts two furrows or excavations simultaneously.

35 When the receptacle is full, the operator stops the machine, elevates the excavator devices 25 above the ground by actuating the members 32 as before described, and moves the machine to the place where the

40 load is to be discharged. The operator then releases the catch devices 72 by actuating the handle 71, when the preponderating weight of the load in advance of the centering member 60 will cause the receptacle to

45 automatically move toward discharging position. As the receptacle thus starts to move, the links 69 will swing the closure 66 upon its pivot 65 into open position as indicated by dotted lines in Fig. 1, and permit 50 the load to pass from the receptacle.

As the receptacle moves into the discharging position the pin 79 passes over the locking device 75—76 and is engaged in the recess 78 and its return prevented by the 55 action of the springs 80, until manually released by the operator actuating the releasing device 83—84 through the pull rod or cable 85.

60 The receptacle 63 is thus held in open or discharging position for a sufficient length of time to permit all the contents of the receptacle to flow therefrom and preventing the relatively powerful springs 88 from prematurely returning a partly discharged receptacle to load receiving position.

When the load has been fully discharged, the operator actuates the pull member 85 and permits the springs 88 to return the empty receptacle to receiving position and automatically engaging the pins 73 with the 70 catch devices 72, thus locking the receptacle into load receiving position, as before.

The receptacle when returned to load receiving position causes the reverse action of the links 69 and returns the closure 66 to its 75 former position.

The machine is then returned to the place where the excavating is being accomplished and the excavating operation continued 80 until the receptacle is again loaded.

The apparatus can be constructed of any suitable material or of any required capacity, and adapted without material structural change to tractors of various forms.

The motor, for instance a gasoline motor, 85 will be located upon the frame between the chain belts or tread devices 12 and coupled by suitable devices to operate the various moving parts, but the motor and its connections are not shown, as they form no part 90 of the present invention.

The improved apparatus is designed more particularly for the use in grading or road making operations, but may be adapted for other excavating purposes if desired, and it 95 is not desired to limit the invention to any specific form of grading or excavating.

What is claimed as new is—

1. In an apparatus of the class described, a frame adapted to support excavating and elevating devices, standards swinging upon said frame, a receptacle open at one end and attached to said standards in position to receive the material from said elevating device, the major portion of the receptacle 105 being disposed between its support and open end, a closure for the open end of the receptacle and swingingly mounted upon said frame, means for swinging said closure into open position when the receptacle moves into discharging position, means applied to said standards for automatically returning the receptacle to receiving position when discharged, and a catch device operating to hold said receptacle in load receiving position. 110

2. In an apparatus of the class described, a frame adapted to support excavating and elevating devices, centering devices carried by said frame, a receptacle, bars swinging upon said centering devices and attached to said 120 receptacle nearer one end than the other, segmental tracks carried by said frame, bearing rollers carried by said receptacle and operating on said tracks, a spring connected to said bars and operating to hold the receptacle 125 in load receiving position, and a catch device operating to hold said receptacle in load receiving position, said receptacle adapted to be moved into discharging position against the resistance of spring by the gravity of its 130

load when the catch is released, and returned to load receiving position by the reaction of the spring when discharged.

3. In an apparatus of the class described, 5 a receptacle adapted to receive excavated material and mounted to swing with the minor portion of the load at one side of its center of motion, yieldable means operating to hold the receptacle, when empty, in load receiving position, and releasable means operating to hold the receptacle in load receiving position against the force exerted by the gravity of the load, whereby the loaded receptacle will be moved into discharging position by the 10 gravity of its load against the resistance of the yieldable means when the releasable means is operated, and returned when discharged to load receiving position by the reaction of the yieldable means.
- 15 4. In an apparatus of the class described, a frame adapted to support excavating and elevating devices, centering devices carried by said frame, a receptacle, bars swinging upon said centering devices and attached to 20 said receptacle nearer one end than the other, a spring connected to said bars and operating to hold the receptacle in load receiving position, and a catch device operating to hold said receptacle in load receiving position, 25 said receptacle adapted to be moved into discharging position against the resistance of the spring by the gravity of its load when the catch is released, and returned to load receiving position by the reaction 30 of the spring when discharged.
- 35 5. In an apparatus of the class described,
- a receptacle adapted to receive excavated material and mounted to swing with the major portion thereof at one side of its center of motion, yieldable means operating to hold the receptacle, when empty in load receiving position, releasable means operating to hold the receptacle in load receiving position against the force exerted by the gravity of the load, and releasable means for locking 40 said receptacle in discharging position, whereby the loaded receptacle will be moved into discharging position by the gravity of its load against the resistance of the yieldable means when the first mentioned releasable means is operated and locked in position by the last mentioned releasable means.
- 45 6. In an apparatus of the class described, a receptacle adapted to receive excavated material and mounted to swing with the major portion thereof at one side of its center of motion, yieldable means operating to hold the receptacle, when empty, in load receiving position, releasable means operating to hold the receptacle in load receiving position 50 against the force exerted by the gravity of the load, a locking bar pivoted at one end and extending at the other end into the path of the receptacle, means for yieldably supporting said locking bar in receptacle engaging position, means for releasing said locking bar, and means for actuating said first mentioned releasing means.

In testimony whereof I affix my signature hereto.

CHARLES A. DOUD.
